UNITED STATES PATENT OFFICE.

FRED L. BORCHERT, OF ROCKFORD, ILLINOIS.

SPRING LATCH.

Application filed May 17, 1926. Serial No. 109,581.

This invention relates in general to miscellaneous hardware and has more particular reference to a spring latch especially designed and adapted for use in connection with hinges or any pivotally connected parts for holding them in closed position or any adjusted angular position.

In the preferred embodiment, my invention is applied to hinges and is particularly advantageous where a latch is employed in connection with a hingedly mounted part such as a door, lid, or like swinging part for holding such part in a closed position or in any adjusted angular position. In said preferred embodiment, my invention is a substitute for and takes the place of any of numerous makes of latches or latch devices now in common use and when so applied it obviates the disadvantages of such devices. For example, in the manufacture of furniture, it is customary to employ some sort of latch device operating between a swinging door or lid and the door jamb which requires that complementary parts be set, one in the door and the other in the door jamb, or in like relation, adapted to interlock either by manual operation or automatically as by a spring-pressed element, depending on the particular construction of such device. These prior devices are objectionable for the reason that, in addition to their cost, they require special labor in accurately setting and adjusting them in position and, in the event that the hinged parts sag or become relatively displaced, the complementary latch parts do not function properly and in some cases are rendered inoperative, thus necessitating resetting. Furthermore, in the manufacture of furniture and other articles where latch devices are used in large quantities, the accumulated cost of such devices, together with the labor cost, is considerable. These conditions are improved by my invention which provides a novel spring latch directly associated with and operating between the hinge-leaves, if applied to a hinge, or between the pivoted parts if they are otherwise pivotally connected. My improved spring latch may be built into the hinge so as to be a part thereof or it may be in the form of an attachment or a supplemental part which may be manufactured and sold independently of the hinge and applied wherever needed. Inasmuch as the spring latch serves the same purpose as the prior latch devices above referred to and is mounted or carried directly in association with the hinge or hinge mounting, it eliminates the remote mountings above referred to and does not require subsequent adjustment or setting and is an economy in cost of manufacture and installation.

Another purpose of my invention is to provide as a new article of manufacture a spring latch of the character above described.

In furtherance of the foregoing my invention in the preferred embodiment contemplates the provision of a spring-pressed ball and a suitable carrier therefor applied or adapted to be attached to one hinge-leaf of a hinge and adapted to snap over an edge or part of or on the other hinge-leaf in the case of application to a hinge. The construction and arrangement of these parts is particularly advantageous and desirable, as will appear hereinafter.

Other objects and attendant advantages will be appreciated by those skilled in this art as the invention becomes better understood by reference to the following description when considered in connection with the accompanying drawing, in which—

Figure 1 is a face view of a hinge equipped with my improved spring latch;

Fig. 2 is a side view of the hinge;

Fig. 3 is a section taken on the line 3—3 of Fig. 1 showing the hinge, mounted;

Fig. 4 is a section similar to Fig. 3 showing another embodiment of my invention; and

Figs. 5 and 6 are views of blanks used in the forms shown in Figs. 3 and 4, respectively.

Referring to Figs. 1, 2, 3, and 5, the hinge shown comprises hinge-leaves 7 and 8 of conventional form having knuckles joined by a pintle 9, in this instance each hinge-leaf having two holes 11 for the passage of wood screws or other means for securing the hinge to the parts to be connected. In this instance the spring latch above referred to becomes a part of the hinge in the sense that its manufacture is combined with the hinge so as to produce a combined hinge and spring latch. As shown in Fig. 5, the hinge-leaf 7 is formed of a single piece of sheet metal, the marginal side 12 of which is bent along the line 13 to a position at right angles to the hinge-leaf proper. Said body is slit from the ends 14 and the ends 15 of said marginal portion are turned inwardly at 16 to provide spring retainers. A flat spring 17 is interposed between said spring retainers with its ends engaged therebeneath and the corners 18 of said ends 15 are turned down to engage and hold

the spring from lateral displacement and at the same time permitting the ends of the spring to have sliding movement with respect to the retainers when the spring is flexed, as will be presently noted. The marginal portion 12 has an aperture 19 in which is seated a ball 21 between said marginal portion and the spring 17. It will be apparent that the spring holds the ball seated with a portion thereof projecting beyond the face 22 of the sheet metal portion 12 and that this projecting portion is adapted to snap over the edge 23 of the hinge-leaf 8 when moved to the closed position shown in Fig. 3, thus holding the parts in this position.

In the application of the hinge just referred to, the hinge-leaf 7 is secured to a stationary part 24 and the hinge-leaf 8 to a swinging part 25 such as a door, lid, or the like. It will be apparent that the spring latch effected by engagement of the ball 21 with the edge of the hinge leaf 8 holds the hinged parts in closed relation but permits release therefrom upon swinging the hinged part 25 in a counter-clockwise direction, viewing Fig. 3, with sufficient pressure to displace or retract the ball into its container or holder against the influence of the spring 17. A spring latch of this character is particularly advantageous for reasons, among others, that the arrangement is compact, a comparatively long spring action is permitted without weakening or crystallizing the spring, and the structure is capable of manufacture at a comparatively low cost. If desired, the parts may be so proportioned that the spring latch per se will be located beneath the face 26, indicated by dotted lines in Fig. 3, so that this side will be flush or unobstructed.

In Figs. 4 and 6, I have shown another embodiment of my invention in which the spring latch is manufactured as a separate article adapted for application or attachment to a hinge or the like. In this particular instance it is of the same general proportions to the hinge above described. As shown in Fig. 6, a sheet metal stamping 27 is provided similar in shape and proportions to the hinge-leaf 7 with the exception that the knuckle parts are omitted. This stamping 27 is formed to provide a ball and spring retainer the same as in the previous case. As shown in Fig. 4, the part 27 is seated against the hinge-leaf 7 and secured in position by the same screws which

hold said hinge-leaf. In this form of the invention the spring ball snaps over the edge of the hinge-leaf 8 in the same manner as previously described.

It will be apparent, therefore, that my invention is adapted for embodiment in different forms as, for example, in an article of manufacture such as a hinge or as a separate article of manufacture comprising a spring latch adapted for application to a hinge or the like. In either case the function and advantages of the spring latch are the same. In the practice of my invention, however, that is in the manufacture of the spring latch, it should be borne in mind that changes might be made in the size, shape and proportions of parts to suit the particular application or use, that the latch or catch element 21 need not necessarily be in the form of a ball, and that the spring need not necessarily be mounted in the identical fashion shown. These and other departures from the particular structure shown herein for purpose of illustration merely, may be made within the spirit and scope of the invention as expressed in the appended claims.

I claim:

1. A spring latch comprising a part shaped to fit against a hinge-leaf and to be retained in position by the fastening means therefor, and further shaped to carry a spring-pressed ball adapted to snap over an edge on the other hinge-leaf.

2. A hinge, one hinge-leaf of which carries a spring-pressed ball adapted to snap over an edge on the other hinge-leaf to hold them in closed relation.

3. As a new article of manufacture, a spring latch for a hinge comprising a flat sheet metal piece having one or more screw holes therethrough and having a marginal portion turned up and its ends turned inwardly to form spring retainers, said marginal portion having an aperture intermediate said turned-in ends; a flat spring interposed between and retained by said ends; and a catch element positioned between the marginal portion and spring and projected thereby through said aperture, said catch element being adapted to snap over an edge of a hinge-leaf in the closed position of the hinge.

In witness of the foregoing I affix my signature.

FRED L. BORCHERT.
